(57) **CLAIM**

The ornamental design for a temperature sensor connector, as shown and described.

DESCRIPTION

FIG. 1 is a bottom, right, and rear perspective view of a temperature sensor connector showing the new design; FIG. 2 is a front, right, and top perspective view thereof; FIG. 3 is a top plan view thereof; FIG. 4 is a bottom plan view thereof; FIG. 5 is a left side view thereof; FIG. 6 is a right side view thereof; FIG. 7 is a front elevational view thereof; FIG. 8 is a rear elevational view thereof;

FIG. 9 is a front, left, and top perspective view thereof of the temperature sensor connector shown as an example implementation coupled via a cable to a temperature sensor; and, FIG. 10 is a top plan view thereof of the temperature sensor connector thereof shown as an example implementation coupled via the cable to the temperature sensor.

The broken lines in the figures are shown for the purpose of illustrating portions of the temperature sensor connector and/or environmental matter that form no part of the claimed design.
